UNITED STATES PATENT OFFICE.

PHELPS BROWN, IRA E. HENDRICKSON, HAROLD H. CLARK, AND TERRENCE G. LOUIS, OF SPRINGFIELD, MASSACHUSETTS; SAID HENDRICKSON, CLARK, AND LOUIS AS-SIGNORS TO WICO ELECTRIC COMPANY, OF WEST SPRINGFIELD, MASSACHUSETTS, A CORPORATION OF MASSACHUSETTS.

MAGNETO.

Application filed July 18, 1923. Serial No. 652,352.

To all whom it may concern:

Be it known that we, PHELPS BROWN, IRA E. HENDRICKSON, HAROLD H. CLARK, and TERRENCE G. LOUIS, citizens of the United States, residing at Springfield, in the county of Hampden and State of Massachusetts, have invented new and useful Improvements in Magnetos, of which the following is a specification.

10 This invention relates to improvements in magnetos and is more particularly concerned with the actuating mechanism thereof. This invention is also an improvement on that disclosed in the copending application for U. S. Letters Patent filed by Phelps Brown and Ira E. Hendrickson on June 2, 1923 under Serial No. 643,037.

The general type of magneto, with which this invention is concerned, is that in which 20 an armature is moved substantially in a straight line path toward and away from, and preferably into contact with magnetic poles. The general class of actuating mechanism to which this invention relates, 25 is that wherein the driving spring (for moving the armature away from its poles) is first placed under stress for the armature driving function by mechanism operated by the engine but is incapable of moving the latter until the contact between the armature and poles has been broken,—such contact being broken, after the driving spring has been stressed, by an inelastic transmission of force from engine operated parts, 30 after which the driving spring comes into play and drives the armature away from its poles more rapidly than it would be otherwise driven by the engine.

One example of a magneto and an actuating mechanism of the class above defined 40 will be found in the pending application for United States Letters Patent of Ira E. Hendrickson, Serial No. 504,334, filed September 30, 1921.

45 Movement of the armature away from its poles, in the manner and by the mechanism, above described, is important in that the spark is produced independent of engine speed and an intense spark is produced at 50 cranking and low engine speeds. In certain cases, this sort of actuating mechanism is not so important when the engine is running at high speed and this invention is concerned with the provision of means

whereby either form of operation may be 55 accomplished, when and as desired.

The general object of the invention is to provide, in magneto actuating mechanism of the general type defined, improved means for rendering the drive spring inoperative, 60 when desired, and for driving the armature directly from the engine, as by an inelastic transmission of force therefrom.

Another object of the invention relates to an arrangement of parts for automatically 65 rendering the drive spring inoperative, after the engine has been started.

A further object of the invention is to provide in magneto actuating mechanism of the general class described, means for automatically causing an advance in the ignition spark after the engine has been started.

Other objects and advantages relate to the particular construction and arrangement of parts and will more particularly appear in 75 the following description and in the illustrative embodiment of the invention in the accompanying drawings, in which:—

Fig. 1 is an end elevational view of a magneto embodying the invention; 80

Fig. 2 is a front elevational view thereof;

Fig. 3 is an enlarged fragmentary sectional plan view taken on the line 3—3 of Fig. 1;

Fig. 4 is an enlarged fragmentary front 85 elevational view of a portion of Fig. 2;

Fig. 5 is a cross-sectional view taken on the line 5—5 of Fig. 2;

Fig. 6 is a fragmentary elevational view of a modification of the device shown in 90 Fig. 3;

Fig. 7 is a fragmentary elevational view taken at right angles to Fig. 6; and

Fig. 8 is a diagrammatical view of the magneto proper. 95

In these drawings, there is shown, in full detail, an embodiment of the invention which incorporates many desirable features relating to the particular construction and arrangement of various parts, which, although important and preferred, are not necessarily essential in so far as the broader aspects of the invention, as above outlined are concerned. As to the broader aspects of the invention, the showing is to be taken 100 as an illustrative example of one of many embodiments of the invention.

The invention is not particularly con-

cerned with the magneto structure proper but rather with improved actuating mechanism for a magneto of a given type. Accordingly the magneto structure has not been illustrated in detail and the general type of magneto, with which the invention is concerned, will sufficiently appear from the diagrammatic showing in Fig. 8. The magneto is of the general type in which an armature, such as *a*, is moved in a substantially straight line path to and from, and preferably into and out of contact with magnetic poles, such as the ends of the pair of cores *b*. The latter are magnetically connected to the poles of a suitable magnetic source, such as the permanent magnet *c*. The electrical windings are preferably, although not necessarily, associated with the cores *b* and, as shown, comprise a primary and a secondary coil *d* and *e*, respectively, on each core. The two coils *d* and *e* are electrically connected, as in series, as illustrated, and the terminals of the connected coils *d* are electrically connected to relatively movable breaker points *f* and *g*, a condenser *h* being bridged across the breaker points. The terminals of the connected coils *e* are suitably connected, as indicated, to the ignition device, such as the spark plug *i*.

In Figs. 1 and 2, the ends of the cores *b* clearly appear and the armature *a* is shown in contact with them.

The breaker point *f* as shown in Fig. 2, is adjustably secured in the upper end of a stationary tube *m*. The movable breaker point *g* is carried on the upper end of a cylindrical member *n*, which slides in tube *m* and guides the points *f* and *g* into square engagement. This member *n* also serves, by its weight or mass, which is considerable, to cause the points *f* and *g* to engage with a percussive blow, the effect of which is to slightly peen the engaged contact surfaces and keep them free from pits. The contact faces, by this arrangement, are, in effect, resurfaced at each operation and kept smooth, flat and bright. Attached to the member *n* is a stem *o* which extends freely through a bracket *k* fixed to armature *a*. A spring *p* encircles stem *o* and acts between the upper face of armature *a* and the lower face of member *n*. Below bracket *k* an abutment *q* is adjustably mounted on stem *p*. The points *f* and *g* engage before the armature *a* engages cores *b* and the spring *k* permits continued movement of the armature. Thus, when armature *a* is seated on its poles *b*, the abutment *q* is spaced from the bracket *k* whereby it is not immediately engaged and moved on the downward flight of the armature.

In magnetos of this type, the armature is periodically caused to move rapidly away from its poles *b* and thus cause a substantial change in the flux flowing in the magnetic circuit. The coils *d* are connected, by break-

er points *f* and *g*, in a closed electrical circuit at the time when the armature is in contact with its poles. These coils *d* function to prevent rapid changes in flux in the magnetic circuit and, in effect, hold the flux until the armature has moved a sufficient distance away from its poles to create a substantial air gap, at which time the breaker points are separated and an ignition current generated in coils *e*. The points *f* and *g* are moved into contact as the armature nears its poles and thereby function to prevent any sudden change of flux which might occasionally cause a small "upthrow" spark.

The magneto may be suitably supported from the engine in any suitable way, as by the bracket or frame *A*, from which, as shown, all the actuating mechanism may also be supported, with the exception of the actuating cam 10, which is fixed to an engine driven shaft, such as the cam shaft *S*.

The actuating mechanism embodies a resilient driving means for moving the armature away from its poles, herein shown as a coil spring 11. This spring is stressed at proper intervals by a transmission of force from the engine, as by the movement of eccentric 10, but, even when fully stressed, this spring is insufficient of itself to overcome the forces holding armature *a* to its poles. For overcoming such forces and starting the armature on its downward flight, a tripping device 12 is employed which after the spring 11 has been stressed comes into play to remove the armature from its poles by an inelastic transmission of force from engine operated parts, such as the eccentric 10. The actuating mechanism also includes suitable means for returning the armature to its poles, herein shown as including a coil spring 13. The force acting to hold the armature to its poles, as herein illustrated, is that due to magnetic attraction.

The actuating mechanism, as above broadly defined, is not a feature of the present invention but rather a definition of the general class of mechanism to which the invention is adapted. The invention, according to one feature, is characterized by the provision of means for rendering the drive spring inoperative when desired and, as to a second feature, of automatically effecting with the above object an advance in timing. The means for accomplishing both objects consists of a member 14 which is movable into position to cooperate with member 12 and prevent the preliminary stressing of the drive spring and cause the armature to be tripped, or started away from its poles, at an earlier time than it otherwise would be.

The invention, in addition to the features above described, contemplates the provision of certain advantageous and desirable features, as improvements in armature actuat-

ing mechanism of the general class described, which features relate to the particular mechanism illustrated herein. As to the broader features of the invention, the details 5 of the particular mechanism, described below, may be varied within wide limits and still embody the invention.

In conjunction with the armature actuating mechanism two arms 15 and 16 are pivotally mounted intermediate their ends on a common stud 17 carried by frame A. The drive spring 11 is mounted between the outer ends of these arms and tends to separate them. The tripping device 12 is adjustably secured to one of these arms, as 16, near the same end but in an offset location, as shown in Fig. 1. The return spring 13 acts between a suitable spring seat on the inner end of arm 16 and a stationary spring seat 18 is provided on frame A. The inner ends of both arms 15 and 16 lie between the spaced arms 19 of a fork 20 fixedly secured to the lower face of armature a. The inner ends of arms 15 and 16 overlie, respectively, a stud 8 fixed on and extending between arms 19. The arm 16 is provided with an abutment 21 which is located in the path of a cam follower 22, herein shown as a third arm pivoted coincidentally with the first and second arms 15 and 16 on the stud 17.

The abutment 21 is preferably adjustable, being in the nature of a cap screw threaded into arm 15, or a lug 23 thereon, and held in adjusted position by a lock nut 24.

The tripping device 12 is also adjustably mounted, being in the nature of a cap screw threaded into arm 16 and held in adjusted position by a lock nut 26.

The spring 11 is also adjustable for its lower spring seat 27 is mounted on a screw 28, threaded into arm 16 and held in adjusted position by a lock nut 29.

The device for rendering the drive spring 11 inoperative is formed as an integral portion of a lever 30 by bending over a portion thereof, as shown in Fig. 4. The lever 30 is pivotally held to arm 15 by a cap screw 31, as shown in Fig. 4. In order to releasably hold the lever 30 in either of the two positions which it may assume, arm 15 is provided with two pairs of recesses 32 and 33 in its lower face, as shown in Fig. 4. A circular disc 34, loosely encompassing the head of screw 31 and yieldingly urged upwardly by the spring 11, has a pair of upturned lugs 35, oppositely located thereon. These lugs 35 pass upwardly through recesses 36 in lever 30 (Fig. 3) and are adapted to enter either pair of recesses 32 or 33. When engaged in the former, as shown, the lever 30 is so held that the device 14 is entirely out of the path of member 12 but when located in the recesses 33, the device 14 directly overlies the member 12.

The spacing means 14 accomplishes its

function manually but the function may be automatically accomplished by the mechanism shown in Figs. 6 and 7. As there shown, the spacing means consists of a cam 40 fitting within a suitable slot in arm 15 70 and pivotally mounted on a stud 41. A spring 42, acting between the head of stud 41 and one face of cam 40 tends to frictionally hold it in position. An operating handle 43, having a weighted outer end 44 is provided for moving cam 40. A stop 45 is provided on arm 15 to limit the upward swinging movement of arm 43 and, when the arm is positioned as shown in full lines in Fig. 6, the cam 40 does not extend below the lower face of arm 15. The spring 42 will hold the cam in this position (which is the starting position) until the engine has been started but after a few strokes of the engine the vibration set up by the arrestation of the armature will cause lever 43 to fall downwardly into the dotted line position in which the cam 40 projects below arm 15 for engagement by member 20. The cam 41 "crosses centers" in moving to its dotted line 85 position and engages a wall 46 on arm 15 as a stop to limit its counterclockwise movement. Consequently, the cam cannot be moved in a clockwise direction by member 12 and remains in the dotted line position, 95 until manually moved.

The operation of the magneto will now be described. For starting the spacing members 14 or 40 are positioned out of the path of member 12. With the parts occupying 100 the relative positions illustrated, the cam 10 will, on continued rotation engage and move follower 22 and the latter will be swung on its pivot 17 thereby engaging abutment 21 and moving arm 16. The time of such engagement can be varied, as desired, by adjustment of the abutment. The left hand end of arm 16 is thus swung upwardly but the left hand end of arm 15, being held against upward movement, by the forces 105 holding armature a to its poles b, is not immediately moved. During the relative movement of arms 15 and 16, the spring 11 is compressed for the subsequent armature driving function. It is to be noted that 115 during the described movement of arm 16, its right hand end moves downwardly thereby drawing away from the armature a and retracting the return spring 13, whereby a path is cleared for the downward flight of 120 the armature.

After spring 11 has been fully stressed the member 12 has been moved into engagement with arm 15 and, on continued rotation of cam 10, the arm 15 is moved and armature a 125 disengaged from its poles. This disengagement, it is to be noted, is effected by an inelastic transmission from the cam. The armature a is, however, moved only a very short distance in this manner for immedi- 130

- ately on the creation of an air gap between the armature and its poles, even though this air gap be very small, the armature supporting force of magnetic attraction is very 5 much diminished and continues to diminish at a very rapidly increasing rate, so that almost immediately the force of the stressed spring 11 becomes superior to that of magnetic attraction and the spring expands and 10 moves armature *a* downwardly more rapidly than it would be moved by member 12. In other words the arm 15 is forced away from member 12 during the downward flight of the armature.
- 15 Continued rotation of the cam 10 eventually allows follower 22 to move radially inward toward shaft S and thus arm 16 is allowed to move under the force of spring 13, whereby the armature is carried upwardly 20 and again seated on its poles. The follower 22 is free to move in one direction relatively to arm 16 and may move slightly away from arm 16. At such times the spring 13 functions also as a supporting force for armature 25 *a* but this force, as has been described, is relaxed entirely during the stressing of the drive spring so that magnetic attraction is the only armature supporting force functioning at that time.
- 30 The operation, thus far described, has been found useful and advantageous and it is particularly effective on starting or low engine speeds because the armature movement is effected independently of, and at a 35 higher speed than, engine speed. However, on higher speeds, a spark of even less intensity than that required for starting will suffice and, moreover, a more rapid armature speed may then be imparted directly from 40 the engine than at starting. In many cases, direct operation of the armature from the engine during its higher speeds is desired and to permit such operation, the member 45 14 is swung into overlying relation with member 12. This, as will be evident from Fig. 1, will substantially prevent the stressing of spring 11 in the manner described and will cause the armature to be not only removed but moved during its entire downward flight by an inelastic transmission of 50 force from the cam. The two arms 15 and 16 do not then have any substantial relative movement on the downward flight of the armature and the latter is, as a practical matter, directly connected to the engine. The 55 return spring 13 functions, as formerly, to return the armature, this being necessary in the embodiment illustrated, on account of the loose connection of follower 22 with arm 60 16. It will be noted that the armature *a* is removed from its poles at an earlier point in the engine cycle than formerly, whereby the spark is automatically advanced as is desired for high speed running. Also it is 65 insured that the spark is retarded, as it

should be for starting, for unless member 14 is moved to the illustrated position, only a small current will be produced which is rarely sufficient for starting. Consequently, the operator is forced to move the member 70 14 to the illustrated position to cause the production of a sufficient spark to start the engine and, when member 14 is thus moved, the spark is automatically retarded.

As above alluded to, with the use of the 75 cam 40 the drive spring 11 is automatically rendered ineffective after the engine has been started and the spark is, at the same time, automatically advanced.

The particular contour of cam 10 and the 80 manner in which it coacts with follower 22 are particularly important because of the resulting effects obtained in the operation of the armature and the interrupter mechanism. The greater portion of the cam is 85 concentric with shaft S and the "rise" portion thereof is formed by the two outwardly converging faces 10'. In the counterclockwise rotation of cam 10, one of these faces 10' will eventually move into parallel 90 and contiguous relation with the follower 22. This condition occurs after the cam has turned nearly sixty degrees from the position illustrated. Thereafter, the contiguous faces commence to move out of parallelism, 95 which results in movement of the follower. The movement of the latter is, however, very slow in the initial stages and later increases, becoming very rapid in its latter stages as the point of the cam nears its 100 engagement with the follower. Continued rotation of cam 10 produces reverse motion of the follower and this motion is very fast in its initial stages and slows down near its final stage and gradually decreases to zero. 105

By this arrangement, the armature which, as has been noted, is held by magnetic attraction to its poles, is barely "cracked" from its poles by a slow movement and may be said to be pried off, as distinguished from 110 a dislodgement due to a sudden blow. As a result, the removal of the armature is effected relatively quietly and without the shocks and jolts which would occur were the initial movement of follower 22 a rapid 115 one. The breaking of the magnetic hold is the severest part of the operation and results in the greatest strains and is therefore accomplished at slow speed. After the high initial resistance to armature movement has 120 been overcome, the movement of the follower becomes much more rapid and during this rapid portion of the flight, bracket *k* engages abutment *q* and quickly separates the breaker points. It is to be noted that 125 the timing of the spark is controlled by the time when bracket *k* and abutment *q* engage and that such wear as occur on the cam, due to the heavy duty of removing the armature, does not alter the timing of the spark for 130

8 this is controlled by another part of the cam, which is not subjected to heavy duty and does not readily become worn. The armature in its return flight moves very rapidly at first and the advantage of this is the speed applied to point *g*, which, with the attached mass *n*, serves to cause point *g* to engage point *f* percussively for the purpose of keeping them clean, flat and bright.

10 After the engagement of the breaker points, the armature moves at gradually decreasing speed for the purpose of seating the armature on its poles in a relatively quiet manner.

15 The invention has been disclosed herein, in an embodiment at present preferred, for the purposes of illustration but the scope of the invention is defined by the appended claims rather than by the foregoing description.

20 Claims:

1. In a magneto, of the type wherein an armature is moved into and out of contact with magnetic poles, a pivoted arm engageable with the armature and adapted to move 25 it away from its poles, a second pivoted arm carrying an abutment adapted to engage and move the first arm, cam means adapted for operation from the engine, and a follower interposed between said means and the second arm.

2. In a magneto, of the type wherein an armature is moved into and out of contact with magnetic poles, a pivoted arm engageable with the armature and adapted to move 35 it away from its poles, a cam adapted for operation from the engine, a cam follower, a member interposed between the follower and said arm, and an adjustable abutment interposed between said arm and member 40 and carried by one thereof.

3. In a magneto, of the type wherein an armature is moved into and out of contact with magnetic poles, a pivoted arm engageable with the armature and adapted to move 45 it away from its poles, a cam adapted for operation from the engine, a cam follower, a member interposed between the follower and said arm, and an adjustable abutment interposed between said follower and member 50 and carried by one thereof.

4. In a magneto, of the type wherein an armature is moved into and out of contact with magnetic poles, a pivoted arm engageable with the armature and adapted to move 55 it away from its poles, a cam adapted for operation from the engine, a cam follower, a member interposed between the follower and said arm, and adjustable abutments carried by said member one of which is adapted 60 for engagement with said arm and the other with said follower.

5. In a magneto, of the type wherein an armature is moved into and out of contact with magnetic poles, two arms pivoted intermediate their ends and near one end

operatively engaged with the armature to move it in opposite directions, an abutment carried by one of said arms near its other end adapted to engage the other arm, an actuating cam, and a pivoted arm engageable by the cam and adapted to engage and move one of the first named arms near its last named end. 70

6. In a magneto, of the type wherein an armature is moved into and out of contact with magnetic poles, two arms pivoted and pivotally connected intermediate their ends and near one end operatively engaged with the armature to move it in opposite directions, an abutment carried by one of 75 said arms near its other end adapted to engage the other arm, an actuating cam, and a cam follower pivoted coincidentally with the first named arms and adapted to engage one of the latter near its last named end. 80

7. In a magneto, of the type wherein an armature is moved into and out of contact with magnetic poles, two arms pivoted and pivotally connected intermediate their ends and near one end operatively engaged with 90 the armature to move it in opposite directions, an abutment carried by one of said arms near its other end adapted to engage the other arm, a spring interposed between said arms adjacent said abutment, an actuating cam, and a pivoted arm engageable by, 95 the cam and adapted to engage and move one of the first named arms near its last named end.

8. In a magneto, of the type wherein an armature is moved into and out of contact with magnetic poles, two arms pivoted and pivotally connected intermediate their ends and near one end operatively engaged with 100 the armature to move it in opposite directions, an abutment carried by one of said arms near its other end and adapted to engage the other arm, a spring interposed between said arms adjacent said abutment, an actuating cam, a pivoted arm engageable by, 105 the cam and adapted to engage and move one of the first named arms near its last named end, and a cam follower pivoted coincidentally with the first named arms and adapted to engage one of the latter near its 110 last named end.

9. In a magneto, having two magnetic poles with which an armature is periodically engaged and disengaged to connect and disconnect the same, a pivoted lever having a part for engaging the armature and moving it away from said poles, a movable member, a spring tending to force said member against the armature and the latter toward its poles, and means adapted for connection to an engine for actuating said lever and for moving said member away from the armature. 120

10. In a magneto, of the type in which an armature is moved into and out of con- 130

- tact with magnetic poles, an arm pivoted intermediate its ends and having one end adapted to move the armature away from its poles, a second arm pivoted intermediate its ends and having one end adapted to move the armature toward its poles, means carried by the other end of one of said arms adapted to engage the other arm and move the same, and means adapted for 10 operation under the control of the engine for oscillating said arms.
11. In a magneto, of the type in which an armature is moved into and out of contact with magnetic poles, an arm pivoted intermediate its ends and having one end adapted to move the armature away from its poles, a second arm pivoted intermediate its ends and having one end adapted to move the armature toward its poles, means carried by the other end of one of said arms adapted to engage the other arm and move the same, actuating means adapted for 20 operation under the control of the engine, and a third pivoted arm interposed between such 25 means and the second arm.
12. In a magneto, of the type in which an armature is moved into and out of contact with magnetic poles, actuating mechanism for moving the armature to and from its poles including means whereby the armature may be moved away from its poles entirely by an inelastic transmission of force, said means constructed to remove the armature from its poles gradually at a relatively 30 slow rate and subsequently move the armature at relatively high speed.
13. In a magneto, of the type wherein the armature is held by magnetic attraction to its poles, mechanism whereby the armature 35 may be moved away from its poles entirely by an inelastic transmission of force and initially effective at a relatively slow speed to pry the armature from its poles and subsequently effective to move the armature at rapidly increasing speed.
14. In a magneto, of the type wherein the armature is held by magnetic attraction to its poles, mechanism whereby the armature may be moved away from its poles entirely by an inelastic transmission of force and initially effective at a relatively slow speed to pry the armature from its poles and subsequently effective to move the armature at rapidly increasing speed, followed 40
- by a comparatively rapid initial return movement of the armature which gradually decreases in speed to seat the armature on its poles relatively quietly.
15. In a magneto, of the type in which an armature is moved into and out of contact with magnetic poles, a cam, and connections between the cam and armature to move the latter to and from its poles, said cam having a concentric dwell portion and two outwardly converging faces substantially tangential to said dwell portion.
16. In a magneto, of the type in which an armature is moved into and out of contact with magnetic poles, a cam having a concentric dwell portion and two outwardly converging faces substantially tangential to said dwell portion, and mechanism connecting the cam and armature including a follower having a flat face which is adapted to be initially engaged by one of said cam faces, the faces initially engaging in substantially parallel and contiguous relation.
17. In a magneto, of the type wherein the armature is held by magnetic attraction to its poles, mechanism whereby the armature may be moved away from its poles entirely by an inelastic transmission of force and initially effective at relatively slow speed to pry the armature from its poles and subsequently effective to move the armature at rapidly increasing speed, followed by a comparatively rapid initial return movement of the armature which gradually decreases in speed to seat the armature on its poles relatively quietly, breaker point mechanism associated with the magneto and including cooperating and relatively movable breaker points, means movable with the armature for disengaging them at an intermediate point in the flight of the armature away from its poles and while the armature is moving at high speed and for engaging them at an intermediate point in the return flight of the armature and before the final slow movement of the approach of the armature to its poles.
- In testimony whereof we have affixed our signatures.
